UNITED STATES PATENT OFFICE.

CLARENCE E. SAFFORD, OF DETROIT, MICHIGAN, ASSIGNOR TO AMERICAN PRESSWELD RADIATOR CORPORATION, OF DETROIT, MICHIGAN, A CORPORATION OF DELAWARE.

RADIATOR.

1,242,984.

Specification of Letters Patent. Patented Oct. 16, 1917.

Application filed May 5, 1913, Serial No. 765,640. Renewed March 1, 1917. Serial No. 151,682.

To all whom it may concern:

Be it known that I, CLARENCE E. SAFFORD, a citizen of the United States, and a resident of Detroit, in the county of Wayne and State of Michigan, have invented a new and Improved Radiator, of which the following is a specification.

This invention relates to the construction of radiators adapted to be heated by the combustion of inflammable gases, such as natural and artificial gas, and its object is to provide a readily controlled burner for such gases which will be particularly efficient in connection with radiators.

15 The invention consists in combination with a radiator comprising a series of sections connected together into groups, of a burner section connecting and separating said groups, of means for conducting gas under pressure 20 to said burner and means for conducting air under pressure to said burner, together with valve means for governing the entrance of the gas and air under pressure. The invention further consists in the details of construction shown, described and particularly 25 pointed out in the claims.

In the accompanying drawings Figure 1 is an elevation of a radiator provided with my improved burner, the upper portion of 30 the burner chamber being in section. Fig. 2 is a section on the line II—II of Fig. 1. Fig. 3 is a rear view of the burner chamber. Fig. 4 is a section on the line IV—IV of Fig. 2. Fig. 5 is a section on the line V—V of Fig. 4. Fig. 6 is a diagrammatic view illustrating the controlling device of this radiator.

Similar reference characters refer to like parts throughout the several views.

40 The sections 1 on each side of the middle section in Fig. 1 are of any desired construction and number, and are connected at top and bottom by bolts 2 and 3 which extend through the openings in the faces of 45 the sections by which the passages in the interiors of these sections communicate. The hot burnt gases from the burner section pass laterally into the upper portions of the side sections 1 and down through the same 50 to the bottoms of the side sections, and from them laterally back to the central section. As shown in Figs. 1 and 2, this central section has a longitudinal portion 4 divided from the upright tube 5 by means of a plate 55 6. The horizontal portion 4 is preferably

provided with a threaded sleeve 7 into which the discharge pipe 8 for the burnt gases may be screwed.

A pipe 9 screws into a threaded sleeve 10 on the vertical tube 5, and connects to a source 60 of air under pressure, a blower 12 being preferred. Within this upright tube 5 is a circular valve 13 mounted on a stem 14, which stem has a lever arm 15 which carries a pin 16 that is slidable in a slot 17 in the lever 18. This lever is pivoted on the screw 19 carried by a lug 20 on the bracket 21, which bracket may have other lugs 22 by means of which it may be connected to the upright tube 5. 70

Secured to this bracket 21 is a cylindrical cap 23, within which is a spool 24 of proper wire which constitutes a solenoid, the core 25 of which has a downwardly extending stem 26 provided with a pin 27 that extends 75 through the slot 17 in the lever 18. A spring 28 above this core 25 normally holds the core down, and thereby holds the valve 13 in horizontal position across the passage in the tube 5. The spring 28 may be held in 80 central position by means of a pin 29, as shown in Fig. 5.

As shown in Fig. 6, wires 30 and 31 connect to this solenoid spool, the wire 30 connecting to a thermostat 32, while a wire 33 85 connects to this thermostat and to any desired current source, such as the battery 34. A wire 35 may connect this battery to a second solenoid for controlling the flow of gas, which may be connected in series by 90 means of the wire 31 with the spool 24 of the solenoid which controls the flow of air.

Gas is conveyed to this heater by means of a pipe 36 which connects to the valve-body 37, in which is a manually operated 95 valve 38. In this valve-body is a passage 39 which connects to the burner nozzle 40, the wall 41 within this body 37 being pierced to form an opening 43 which may be closed by the extension 44 on the core 45 of the solenoid, which extension constitutes a gas-valve. A spring 48 normally holds this gas-valve on its seat. The solenoid has a spool 46 which is covered by a shell 47 connecting to the valve-body 37. The wires 31 and 35 105 shown in Fig. 6 connect to the wire of this spool 46. When the temperature in the room, wherein the thermostat 32 is mounted, falls below a predetermined certain degree, the connection between the wires 30 and 33 110

will be closed by the thermostat 32 and the two solenoids will be energized. This will result in their cores 25 and 45 being drawn up, permitting gas to flow up through the 5 pipe 36 through the valve-body 39 and the burner nozzle 40. At the same time the valve 13 will be turned from its normal horizontal position across the pipe 5 to the vertical position shown in Fig. 2 so as to 10 permit a flow of air through the pipe 9 upward through the tube 5 of the middle section, around the nozzle 40 into the mixing chamber.

The gas burner is formed of a rectangular 15 cap 50 corrugated transversely to the radiator, as shown in Fig. 1. The upper portions of these corrugations are formed with narrow slits 52 through which the mixed air and gas can pass. This cap 50 is held in 20 position on the mixing chamber 53 of the burner by means of screws 54. Secured against the sides of this cap 50 by means of screws 55 are the side plates 56, which have flanges 57 and lugs 58 to position the curved 25 plate 59. Extending around the outer edges of these plates 56 and down to the front and rear edge of the mixing chamber 53, as shown in Fig. 2, is a cover plate 60. This insures an air chamber around the 30 curved plate 59 which becomes very hot and would scorch any animal and vegetable matter touching it. Within the body 51 and surrounding the upper end of the nozzle 40 is a small cap 62 generally circular in cross 35 section, having a series of longitudinal slots 63 through which the gas may escape from the nozzle 40. The upper end of this cap 62 has a central depression 64 against which the gas will impinge and flow out laterally 40 through the slots 63.

If desired, the burner chamber may be provided with a door 65 having a locking button 66, which door has a transparent portion 67 and is mounted on pins 68 carried 45 by the lugs 69 on the frame 70 between the plates 57 and 59, as shown in Fig. 2. This door is provided to permit igniting the gas at the upper end of the pilot light tube 72. The gas is controlled by a valve 73 from 50 which a pipe 74 connects into the valve-body 37 below the manually-controlled valve 38, the valve-body having an opening 75 into which this pipe 74 extends.

The main advantage of this radiator construction lies in the fact that the air and 55 burnt gases within the sections are under pressure so that the hot gases will be of substantially the same density at the tops of the sections 1 as at the bottom. As a result, 60 heat will be transmitted from the burnt gases to the walls of these sections and radiated by them, as the dense gases pass downward, and, because of the comparatively slow movement of these gases, the area of 65 the pipe 8 being very small in proportion to

the combined cross-sectional area of the sections 1, substantially all the heat in these gases will be taken up by the wall of the sections.

The thermostat 32 may be of any desired 70 construction and located at any desired place. Whenever the temperature falls below the desired degree, the solenoids will be energized and the gas and air will be permitted to flow to the mixing chamber, and 75 through the slots 52 into the burner chamber where it will be ignited by the pilot light at the end of the pipe 72. By placing the cap 62 over the end of the nozzle 40, a thorough 80 mixture of gas and air is attained. The plate 59 becomes very hot, sufficiently so to scorch cloth or any part of the human body touching it. A shield is therefore placed 85 over it in the form of a plate 60, which is separated from the plate 59 by an air space. 90

When the temperature has risen to a sufficient 95 degree, the electric circuit will be broken, permitting the valves 13 and 44 to close the air and gas passages. The valve 13 is of value as it prevents the blast of air 100 from the blower from being wasted, the power required to drive the usual type of fan blowers being substantially in proportion to the amount of air propelled thereby. The various details of construction and 105 proportions of the parts may all be changed to meet the different requirements without departing from the spirit of my invention as set forth in the hereto annexed claims.

I claim:

1. In a radiator, the combination of a group of sections, each section having inlet and outlet openings at their upper and lower ends respectively, a burner section connected to said group of sections and having an outlet and an inlet opening at its upper and lower ends respectively communicating with openings in the adjacent section, an air inlet opening and a burnt-gas outlet opening in 105 said burner section, a plate in the burner section separating the said section below the air-inlet and above the burnt-gas outlet, a burner within the burner section, a gas supply therefor, and valves to admit air and gas to said burner.

2. In a radiator, the combination of a burner section comprising a burner chamber, a mixing chamber, an air passage and a burnt-gas chamber, an air inlet pipe connecting to the air passage, a controlling valve 120 in said air passage, a gas-inlet pipe connecting to the mixing chamber, a valve in said pipe, a partition separating the burnt-gas chamber from the air passage, and a plurality of heating sections connected to said 125 burner section, said sections having openings at their upper ends through which the burnt gases may pass from the burner section to the heating sections, and at their lower ends through which the burnt gases may pass 130

from the heating sections to the burnt-gas chamber, and means to control said valves.

3. In a radiator, the combination of a burner section comprising a burner chamber, a mixing chamber and an air passage in connection with each other, an air inlet pipe connecting with the air passage and with a source of air under pressure, a gas pipe connecting with the mixing chamber and with a source of gas under pressure, valves controlling the passage of air and gas to the mixing chamber, means for opening said air and gas valves, and heater sections adapted to receive the burnt gases from the upper end of the burner section.

4. In a radiator, the combination of a burner section comprising a burner chamber having an arched top and lateral discharge openings, a protecting shield above the burner chamber and separated therefrom by an air space, a mixing chamber be-

low said burner chamber and an air passage connecting with said mixing chamber and with a source of air under pressure, a valve in said passage, a gas nozzle extending into said mixing chamber and connecting with a source of gas under pressure, a valve to permit the flow of the gas, a plurality of groups of heater sections having openings at their upper ends to receive the burnt gases passing out of the lateral discharge openings in the burner chamber, said sections having discharge openings at their lower ends, and a pipe for conveying away the burnt gases from said radiator.

In testimony whereof I have signed this specification in the presence of two subscribing witnesses.

CLARENCE E. SAFFORD.
